UNITED STATES PATENT OFFICE.

DENIS WILLIAM DALEY, OF PARKERSBURG, WEST VIRGINIA.

REMOVABLE SUPPORT FOR SIDES OF CONCRETE-MOLDS.

Specification of Letters Patent.

Patented Nov. 10, 1914.

1,116,805.

Application filed May 3, 1913. Serial No. 765,362.

To all whom it may concern:

Be it known that I, DENIS W. DALEY, a citizen of the United States, residing in Parkersburg, in the county of Wood and State of West Virginia, have invented an Improvement in Removable Supports for Sides of Concrete-Molds, of which the following is a specification.

In molding the walls of concrete or cement structures it is necessary to support horizontally and at different heights the side boards of the molds between which concrete or cement is to be poured to form a section of the wall.

I have devised an improved apparatus for this purpose, and the same is hereinafter described with reference to the accompanying drawing, in which—

Figure 1 is a vertical section of a concrete wall and of my apparatus in place thereon, and supporting side mold-boards in the position required for receiving plastic material between them. Fig. 2 is a sectional perspective view of a concrete wall with my apparatus applied in position to support side mold-boards; and, Fig. 3 is a sectional perspective view of the same parts as shown in Fig. 2, but with mold-boards added and arranged as shown in Fig. 1.

The apparatus is formed of duplicate sets of bars A and B, and two right-angular brackets C and D. The duplicate sets are in practice, arranged on opposite sides of a concrete or cement wall, and are secured together and clamped against the sides of the wall by suitable means, which in this instance is a twisted wire E whose ends extend across the wall section and pass through the bars and are secured temporarily in position by means of pins F. The two bars of each duplicate set are laid together lengthwise and secured in that position by suitable means. The bars A are about one-third ($\frac{1}{3}$) longer than the bars B and project above the latter whose upper ends support side mold-boards G. The right-angular brackets D are so applied that the vertical flange is clamped between the bars A and B, while the horizontal flanges overlie and rest upon the top surface of the concrete wall section already formed. These brackets D serve as the means for supporting the dupli-

cate portions of the supports in due position on the sides of the wall section. When thus applied, side mold-boards G rest upon the brackets and their outer sides lie against the portions of the bars A that project above the bars B. The lower right-angular brackets C serve in practice as supports for weights (not shown) which may be used to hold the bars A and B more firmly in due vertical position, and also preventing the same turning on their axles.

It is apparent that when the mold-boards G are supported in the manner indicated in Figs. 1 and 3, plastic concrete or cement may be poured into the space between them and will thus form an additional or superadded section of the wall. When such added section has set, the pins F are removed from the end of the twisted wire E, which permits detachment and removal of the duplicate supports from the wall.

The bars A and B may be constructed of metal or wood, and the brackets are preferably constructed of metal.

What I claim is:

1. An apparatus for the purpose specified, comprising duplicate sets of bars, the outer ones of each side projecting above the inner ones, and secured thereto and right angular brackets secured to the bars at the upper ends of the shorter ones, the horizontal portions of said brackets projecting inwardly so as to overlap a concrete wall section, and means for securing the duplicate sets together when applied on opposite sides of a wall, as shown and described.

2. An improved apparatus for the purpose specified, comprising a set of bars arranged side by side, and secured together, one of said bars being longer than the other, and right-angular metal brackets whose vertical flanges are clamped between the bars with their horizontal flanges projecting in opposite directions, one of said brackets being at the top of the shorter bar, and the other bracket at the bottom of the longer bar, as described.

DENIS WILLIAM DALEY.
